UNITED STATES PATENT OFFICE

ARTHUR STOCKSTEOM, OF ST. LOUIS, MISSOURI, ASSIGNEE TO AMERICAN STOVE COMPANY, OF ST. LOUIS, MISSOURI, A CORPORATION OF NEW JERSEY

FLUE CONNECTION FOR STOVES

Application filed May 30, 1929. Serial No. 364,573.

This invention relates to improvements in flue connections for stoves, the invention, as will appear from the following description and accompanying drawings, being more specifically directed to and designed as a flue connection for gas ranges having a top cover for cooking burners.

The public demands that kitchen furniture be made more pleasing in appearance grow increasingly stronger each day, and to meet these demands stove designs, particularly gas stove designs have materially changed in recent years. The stove or range illustrated in the accompanying drawings is an outgrowth of this public demand as it will be seen that a hinged or swinging cover is provided for the cooking burners to hide these burners from sight, and the present invention has been conceived to permit this cover to remain down not only when the burners are not in use but also to remain down when actual cooking is taking place. It is only necessary to raise the cover for the purpose of placing utensils on the burners or removing utensils from the burners.

It therefore becomes obvious that I have provided a range which is of most pleasing appearance in that all burners and utensils are hidden from view and which is one of the objects of the present invention.

Another advantage and object which is an outgrowth of the present invention is that cooking under this closed top with the present flue connection insures that all cooking odors are carried off.

A range utilizing the present invention also has the advantage that it will not tend to heat up the kitchen as greatly as do those ranges or stoves of the common and well known type wherein the cooking burners are open and permit the delivery of heat and odors into the room.

Another object of the invention is the provision of a flue connection so constructed as to be operable with and form a part of a swinging top cover or other moving part.

A still further improvement which is an outgrowth of the present invention is that gases, products of combustion and odorous

vapors are carried off from the range so that there is no possibility of them discoloring the walls adjacent to the range.

Other objects, novel features of construction and improved results of the invention will appear from the following description and accompanying drawings.

In the drawings:

Figure 1 is a plan view of a range embodying the present invention.

Figure 2 is a rear view.

Figure 3 is an end view.

Figure 4 is a fragmentary end view similar to Figure 3, the swinging cover being shown in raised or elevated position.

Figure 5 is a fragmentary view in vertical section taken on the line 5—5 of Figure 2.

Figure 6 is a fragmentary horizontal sectional view taken on the line 6—6 of Figure 1.

Figure 7 is a diagrammatic view partly in vertical section illustrating the joining or abutting ends of the stationary and movable portions of the flue.

Reference now being had to the drawings in which the preferred embodiment of the present invention is illustrated and wherein the range to which the present invention is applied comprises at one side the cooking and broiling oven A having the usual outlet flue B having a collar 10 for connection with an outlet pipe or conduit.

At its opposite end the range base 11, which base is incidentally supported above the floor by the usual legs 12 is provided with cooking burners 13 fed from a common gas manifold 14 concealed within a housing 15 having a closed front wall 16, side or end wall 17, rear wall 18 and closed at its other side through abutment with one side of the ovens A.

In gas ranges the cooking burners 13 are beneath either a solid cooking top or are beneath a cooking top composed of a grid. The present invention is applicable to stoves or ranges utilizing either form of cooking top.

The cover for the cooking top is designated at C and in Figure 3 of the drawings it will be seen that it is in its lowered position to close in the cooking burners 13 and for the

purpose of appearance is of a height similar to the difference in height between the burner chamber 15 and the height of the ovens A so that when the cover is in lowered position 5 the cover top 19 is in the same horizontal plane and level with the oven top 20, as clearly is illustrated in Figure 2 of the drawings. This cover is pivotally mounted approximately midway its length and provided 10 with a handle 21 by which it can be raised and lowered.

By reference to Figure 4 the position the cover C assumes in its raised or elevated position will be clearly seen and from this 15 figure it will be apparent that the rear portion of the cover telescopes the burner chamber as the side wall 22 of the cover parallels the end wall 17 of the burner chamber while the top 19 of the cover parallels the back wall 20 18 of the burner chamber.

The cover is provided with a rear wall 23 which is hinged at its upper edge at a plurality of points 24 to the under side of the rear edge of the cover top so that when the 25 cover is in its raised position this cover back 23 parallels the rear wall 18 of the burner chamber as is clearly illustrated in Figure 4 of the drawings and by assuming this position permits the raising of the cover. When 30 the cover is lowered its rear wall 23 falls by gravity into the proper position to close the rear end of the chamber formed by the cover as is clearly evident in Figures 2, 3 and 5 of the drawings.

35 At the rear of the range the ordinary outlet flue B of the ovens is provided with an extension D to which extension is connected the flue E forming a part of the back wall 23 of the cover.

40 As the cover flue E moves with the rear wall of the cover it is necessary to provide a special form of connection between the flues D and

E. In Figures 2, 6 and 7 the construction which makes this possible is illustrated.

45 Here it will be seen that the top 25 of the flue portion D has an extending end 26 beyond the tapered outer end 27 of the rear wall 28 of this flue and that the bottom 29 of the flue ends at the bottom of the taper 27 or in other words is considerably shorter than the top 25 of the flue.

The flue E is made in the reverse manner. That is to say, its outer wall 30 is tapered as at 31 in a reverse direction to the taper 27 of the outer wall 28 of the flue D while its bottom 32 has an outwardly extending end 33 beyond the edge 34 of the rear wall 23 of the cover. The top 35 of the flue stops short of the edge 34 of the cover rear wall 23 or 60 in other words is shorter than the bottom 33 of the flue.

By reason of the construction described and illustrated the two flues D and E can be swung into and out of engagement with 65 one another in a telescoping manner. It will

be seen that the extending portion 26 of the flue D will act as a stop for the top 35 of the flue E as it will overlap upon the flue E as clearly illustrated in Figure 6 of the drawing while the extending portion 33 of the bottom of the flue E will overlap and abut the outer face of the bottom 29 of the flue D as is also apparent in Figure 6 of the drawing. The rear wall 30 of the flue E overlaps the rear wall 28 of the flue D. Thus it will be 70 seen that through these overlapping engagements a continuous flue is provided when the cover is in its lowered or closed position.

75 From the foregoing it will be seen that there is provided a range having all of the attributes and advantages hereinbefore pointed out and at the same time having as a part of its structure a flue arrangement which is necessarily periodically broken and yet at the same time is of such a structure 80 to permit this temporary breaking of the flue in what would be termed an automatic manner as there is no necessity for the loosening or tightening of bolts, screws or any fastening means.

85 The depth or height of the cover is sufficient to form a covered cooking compartment in that it provides sufficient room, when the cover is in closed position, to accommodate cooking vessels of different characters so 90 that cooking can be carried on with the cover down forming a closed cooking chamber with an outlet flue connection for carrying off gases, odors, etc.

95 In the drawings the preferred embodiment 100 of the invention is illustrated in connection with a gas range but the present invention can be used in connection with other stoves without departing from the spirit of the invention, as for instance on stoves or ranges 105 using other forms of fuel as a heating medium.

Having thus described my invention what I claim and desire to secure by Letters Patent is:

110 1. In a gas range having a main outlet flue, a cooking top burner portion and a protecting cover therefor hinged to the top burner structure and adapted to occupy a horizontal position protecting the top burner structure and forming therewith a cooking chamber or to be swung backward to give access to the top burner portion and form a splash back for said structure, and said cover having a flue connection with said main range flue outlet, for the purpose described.

115 2. In a range having a cooking top burner portion and a movable cover therefor adapted to form when in its lowered position a closed cooking chamber above said cooking top and in its raised position a splash back for said structure, and said cover having an outlet flue connection movable therewith communicating with the interior of the cooking chamber, formed by the cover when in its 120 130

lowered position, for the purpose described.

3. A range having at its rear a main outlet flue, a cooking top burner portion, a swinging cover for protecting and forming above said top burner portion a closed cooking chamber, the rear wall of said movable cooking chamber hinged to the cover at the rear edge thereof, said chamber rear wall carrying an outlet flue adapted for telescopic connection with the main outlet flue of the range, and said rear cooking chamber wall adapted to swing upon its hinged connection and parallel the rear wall of the range when the cover is in an elevated position.
- 10 4. A range having at one side an oven and at its rear an outlet flue therefor, a cooking top burner portion adjacent said oven, a removable cover for said cooking top portion, said cover forming when in its lowered position a closed cooking chamber above said cooking burner portion and a splash back for said cooking burner portion when in its elevated position, the rear wall of said combined cover and cooking chamber movably connected to the rear end of said cover top to permit said rear wall to assume a position parallel to the back of the range when the cover is in an elevated position, and said rear cover wall provided with a flue adapted for connection with the main range flue, for the purpose described.

5. The combination with a range having a cooking top burner portion and at one side thereof an oven structure extending above the same, of a swinging cover for the cooking top burner structure, said swinging cover of a depth equal to the height of the oven above the cooking top burner structure to form a closed cooking chamber when the cover is in its lowered position, an outlet flue for said oven structure, and a flue at the rear of said swinging cooking chamber having quick detachable telescopic connection with the main outlet flue of the oven structure, for the purpose described.

6. A gas range comprising an oven having a main outlet flue and a cooking top burner portion, a horizontally pivoted and vertically movable protecting cover for said cooking top and adapted to form thereabove a closed cooking chamber, and an outlet flue for said cooking chamber movable therewith and having automatic quick detachable connection with said main oven outlet flue when the cover is in its lowered position.

7. A range having at its rear a main outlet flue, a cooking top burner portion, a movable cover for protecting and forming above said top burner portion a closed cooking chamber, the rear wall of said movable cooking chamber movably connected to the cover and carrying an outlet flue adapted for communication with the main outlet flue of the range, and said rear cooking chamber wall adapted to move upon its connection and

parallel the rear wall of the range when the cover is in an elevated position.

8. The combination with a range having a cooking top burner portion and at one side thereof an oven structure extending above the same, of a movable cover for the cooking top burner structure, said movable cover of a depth substantially the height of the oven above the cooking top burner structure to form thereabove a closed cooking chamber when the cover is in its lowered position upon the cooking top, an outlet flue for said oven structure, and a flue for said movable cooking chamber extending lengthwise the rear thereof and adapted for quick detachable connection with the main outlet flue of the oven structure, for the purpose described.

9. In a gas range having a main outlet flue, a cooking top burner portion and a protecting means therefor movably connected to the top burner structure and forming therewith a cooking chamber, said protecting means movable to give access to the top burner portion of the range and when moved into said position adapted to form a splash-back for said cooking top burner portion, and said cover having a flue connection with said main range flue outlet, for the purpose described.

10. A gas range comprising a supporting frame having at one end a cooking top burner portion and at its opposite end an oven extending above said cooking top portion, movable means connected to the top burner portion for concealing said portion from view and forming therewith a cooking chamber, the top of which has its edge adjacent the oven in the same horizontal plane with the oven top to form a cabinet range of pleasing appearance, said top burner portion concealing means movable to give access to the top burners, said oven having an outlet flue, and said cover having a flue connection with said oven outlet flue, for the purpose described.

11. A gas range comprising an oven having a main outlet flue and a cooking top burner portion, a movable cover therefor adapted to form when in its lowered position a closed cooking chamber above said cooking top and in its raised position a splash-back for said structure, an outlet flue for said cooking chamber and movable with the cover forming the chamber, said cover outlet flue having quick detachable connection with the main oven outlet flue when the cover is in its lowered position.

In testimony whereof I hereunto affix my signature.

ARTHUR STOCKSTROM.
